BALL VALVE

William J. Baker, Orange, Calif., assignor to Armco
Steel Corporation, Middletown, Ohio

Filed Apr. 23, 1975, Ser. No. 570,806

Term of patent 14 years

Int. Cl. D23—01

U.S. Cl. D23—19

FIG. 1 is a perspective view of a ball valve showing my new design;

FIG. 2 is a front elevational view;

FIG. 3 is a rear elevational view;

FIG. 4 is a right side elevational view;

FIG. 5 is a left side elevational view;

FIG. 6 is a top plan view; and

FIG. 7 is a bottom plan view.

I claim:

The ornamental design for a ball valve, as shown.
